ABSTRACT

A multistable circuit arrangement comprising a multiplicity n of at least three storage stages each of the storage stages possessing two possible operating states each of the n storage stages comprising amplifier stages, each amplifier stage having control inputs and at least one output, a variable coupling impedance operatively associated with each amplifier stage, wherein for each operating state of the circuit arrangement a random one of the n amplifier stages assumes one of both possible operating states whereas all of the other amplifier stages assume the other operating state, until upon actuating a given one of the coupling impedances of the amplifier stages operating in the other operating state the aforesaid one operating state becomes unstable and only the other operating state is possible, so that only the amplifier stage associated with the actuated coupling impedance is positively controlled to assume said one operating state and to remain therein.

MULTISTABLE CIRCUIT ARRANGEMENT

BACKGROUND OF THE INVENTION

The present invention relates to a new and improved construction of multistable circuit arrangement.

There are already known to the art, for instance under the designation ring counters, multistable circuit arrangements having a multiplicity n of at least three controllable storage stages each having two alternate operating states. These circuits contain for instance storage stages which are coupled with one another such that by delivering a first switching pulse the first switching stage can be controlled from a NO-state into a YES-state, by delivering a second switching pulse the second switching stage can be controlled from such NO-state into a YES-state, and by delivering a third switching pulse the third switching stage can be controlled from a NO-state into a YES-state, and so forth.

SUMMARY OF THE INVENTION

It is a primary object of the present invention to provide an improved multistable circuit arrangement comprising storage stages which can be novelly controlled so as to assume an arbitrarily chosen one of two possible operating states.

Another and more specific object of the present invention relates to a new and improved construction of multistable circuit arrangement having three or more storage stages, for example having ten storage stages, wherein, instead of delivering suitable voltage- or current pulses, it is possible through brief actuation of a respective coupling means, such as an impedance associated with each storage stage to control in a random sequence the circuit arrangement to assume each desired one of the number N of possible operating states corresponding to the number n of storage stages, and preferably in the manner that, for instance as is suitable with a ten-key arrangement, by briefly actuating one of the keys 0, 1, 2 . . . 8, 9 a corresponding numerical value can be introduced into a numerical computer or calculating machine or a similar digital data processing device.

For the purpose of realizing the objects of this invention there is resorted to the use of a concept as disclosed in German patent publication No. 2,000,883, filed by the applicants of this development. In such patent as well as in the article entitled "Controlled Stability of Flip-Flop Circuit," by Theo Stutz and Albert Muller, appearing in 12-IEEE-Solid-State-Circuits-D 8758—April 1972, there is disclosed a bistable flip-flop circuit arrangement with two crosswise coupled direct-current amplifiers, where in each of both stable operating states one of the amplifiers is operated to be conductive in an active, differentially amplifying operating range and the other is operated in an inactive, non-amplifying operating range. Each of both amplifiers has associated therewith an alternating-current coupling loop with at least one variable phase-rotating impedance between its output and its input. The coupling elements or impedances together with that one of both amplifiers which is placed in its conductive active, amplifying operating state form an oscillating circuit, the oscillations of which begin as soon as a predetermined value of the variable alternating current-coupling element has been attained. Upon the start of the oscillations the amplifier previously in its active, conductive

and amplifying state is automatically shifted out of this state and the other amplifier is placed into its active operating state. The flip-flop circuit arrangement remains in this newly attained operating state until there is effected a change to a different predetermined value of the alternating current-coupling impedances, which triggers resetting into the first operating state.

Basically, there is employed the recognition that a differentially amplifying amplifier becomes unstable under certain conditions in which the alternating current signals always present as disturbances at the input of an amplifier can be fed back to the amplifier input via an appropriate feedback loop or path from the amplifier output so as to be in-phase and sufficiently amplified. Further, the changes in the direct-current already brought about upon the occurrence of the self-oscillation state is sufficient to switch, via the mutual direct-current coupling path between two amplifiers, the previously non-active and non-amplifying amplifier into its active amplifying operating state and the previously active amplifying amplifier into its inactive operating state. There can be also advantageously employed a variable capacitor as the variable coupling means which can be externally actuated in order to obtain a phase-correct feedback with sufficiently amplified level at the input of an amplifier in an active amplifying operating state. As the variable capacitor there is preferably used an open capacitor, the effective capacitance of which can be increased by bringing into proximity thereto an actuation element, for instance by manually actuating a key or the like.

For the attainment of the previously discussed objectives, namely to devise a multistable circuit arrangement which for instance, through actuating a key bringing about an intended variation of a respective predetermined coupling impedance of n coupling impedances, changes from one defined situation of n possible situations of operating state directly into an arbitrarily selected new desired situation of the operating states, or possibly remains in the original operating state it was important to discover additional measures to be hereinafter defined.

Now according to the invention there is provided a multistable circuit arrangement with a multiplicity n of at least three storage stages each capable of assuming two possible alternate operating states, all n storage stages being constituted by amplifier stages each having control inputs and at least one output. There is further provided a respective associated variable coupling impedance which can be changed by intentional actuation thereof in a predetermined manner and wherein the components are coupled with one another such that in each operating state of the circuit arrangement a random one, but only one of the n amplifier stages is brought into a given one of both operating states, for instance the active amplifying state, whereas all of the other amplifier stages are blocked in their other operating state, for instance the inactive operating state, until upon selectively actuating an arbitrarily selected coupling impedance for the amplifier stages, with the exception of the associated amplifier stage, the given operating state is rendered unstable and only the other operating state is possible, so that only the associated amplifier stage is positively controlled into the given operating state and remains therein.

According to a specific, particularly advantageous construction of the invention it is possible to have each

of the n amplifier stages encompass $n-1$ signal amplifiers each having a respective control input and a respective amplifier output. The outputs of the signal amplifiers of each amplifier stage are each connected via a common collector line with the input of an associated feedback amplifier. The respective output of each such feedback amplifier is directly connected, on the one hand with the similar type outputs of the feedback amplifiers of the other amplifier stages and, on the other hand, is coupled with a respective associated coupling impedance which can be intentionally externally actuated. The other terminal of each such coupling impedance is connected with predetermined inputs of all of the other amplifier stages, but not with any input of the associated amplifier stage, and wherein the arrangement is such that in each operating state of the circuit arrangement all of the signal amplifiers and the associated feedback amplifier of any given one but only one of the n amplifier stages is switched into its active amplifying state, whereas the signal amplifiers of all of the other amplifier stages are switched into their inactive saturation state and the feedback amplifiers of such other amplifier stages are likewise placed into their inactive blocking state until a random coupling impedance is actuated in the sense of increasing its alternating current-transmission mass for the amplifier stages connected therewith and renders impossible the attainment of the active amplifying state, i.e., renders such instable, and thus there is automatically brought about the active amplifying state for the associated amplifier stage and such is maintained thereat.

BRIEF DESCRIPTION OF THE DRAWINGS

The invention will be better understood and objects other than those set forth above, will become apparent when consideration is given to the following detailed description thereof. Such description makes reference to the annexed drawings wherein:

FIG. 1 is a schematic functional diagram of a tristable exemplary embodiment for explaining the desired mode of operation;

FIG. 2 is a block circuit diagram of three storage stages with associated alternating current-coupling paths for realizing the mode of operation discussed in conjunction with FIG. 1;

FIG. 3 is a circuit diagram of a transistorized tristable circuit arrangement of the type depicted in FIG. 2, however showing the required direct-current coupling paths and depicted as an embodiment which can be suitably constructed as an integrated circuit;

FIG. 4 is a circuit diagram, corresponding to the arrangement of FIG. 3, of a storage stage for a ten-fold stable circuit arrangement; and

FIG. 5 is a circuit diagram of a decadic-stable circuit arrangement having ten storage stages according to the arrangement of FIG. 4.

DETAILED DESCRIPTION OF THE PREFERRED EMBODIMENTS

Describing now the drawings, in the functional diagram of FIG. 1 there have been shown three storage stages consisting of amplifiers A, B, C which are mutually coupled by non-illustrated direct-current paths in such a way that at any time one of the amplifiers, but only one such amplifier, for instance as shown in the drawing the amplifier A, can be driven into its active,

differentially operating state, whereas both of the other amplifiers, in this instance the amplifiers B and C, are driven into their inactive, non-amplifying operating state, for instance into their saturation region or their blocking region. Furthermore, the condition of operating states momentarily attained by arrangement which is characterized by the operating state of the amplifier A assuming an active, amplifying operating state is maintained until by virtue of an intentionally brought about switching operation there is attained a change in the condition or situation of the operating states, for instance into a state where one of the other amplifiers, such as the amplifiers B or C is brought into an active amplifying operating state.

Each amplifier A, B and C has two control inputs a_1 , a_2 and b_1 , b_2 , and c_1 , c_2 respectively and a respective output S_a , S_b and S_c respectively. At the output of the amplifier which is in a momentarily active amplifying operating state, for instance at the output S_a of the amplifier A there appear amplified alternating-current signals when there appears at one of the relevant inputs, for instance the input a_1 or a_2 , alternating-current signals. Such appear at any time, for instance, in the form of so-called noise.

Each of the amplifiers A, B, C has operatively associated therewith a variable coupling means or impedance, here constituted by the variable coupling capacitors T_a , T_b and T_c . In the non-actuated state the capacitance of such capacitors T_a , T_b , T_c each possess a relatively small, practically ineffectual residual value, for instance in the order of only a few picofarads (pF). By externally mechanically actuating a given respective one of such capacitors, for instance by actuating a respective associated push button or key, even only briefly, it is possible to alter the effective capacitance of the corresponding coupling capacitor so as to assume a considerably higher working value. According to the showing of FIG. 1, the one respective connection terminals of each of the aforesaid capacitors T_a , T_b , T_c are connected by means of a common lead or line S_r with the outputs S_a , S_b , S_c of all of the amplifiers A, B, C, whereas the other respective connection terminals of these capacitors are each connected to a respective control input of the non-associated amplifier.

Thus, the capacitor T_a associated with the amplifier A is coupled with the input c_1 of the amplifier C and the input b_2 of the amplifier B, the capacitor T_b with the inputs a_1 and c_2 of the amplifiers A and C, and the capacitor T_c with the inputs b_1 and a_2 of the amplifiers B and C. The tristable circuit arrangement depicted in FIG. 1 functions in the following manner:

If, with the illustrated operating state or condition wherein the amplifier A is in an active operating state and the amplifiers B and C are in inactive operating states, there is increased for instance the capacitance of the capacitor T_b , even if only briefly, for instance by actuating an associated actuation key, so as to shift from an ineffectual residual value to a considerably higher effective value, then there is rendered effective an alternating-current feedback path from the inverting output S_a of the active amplifier A via the ring conductor or common lead S_r and the increased capacitance of the actuated coupling capacitor T_b to the input a_1 of the active amplifier A, with the result that the active operating state of this amplifier A is rendered instable. In this instance, the alternating-current signals, which are always present as disturbance at the active amplifier A, are amplified and transmitted to its output S_a .

and via the ring conductor or common lead S_r and the increased capacitance of the coupling capacitor T_b they are fed back in proper phase relation i.e. in-phase, with sufficiently great amplitude to the amplifier input a_1 in such a manner that the active operating state of such amplifier A is rendered unstable, i.e., there is fulfilled a self-oscillating condition for such amplifier. Upon the start of an oscillation, practically already during the first half-wave, and under the influence of the direct-current coupling path the previously active amplifier A is controlled such as to assume its operating state, for instance it is shifted into its saturated state, so that as required one of both of the other amplifiers will be shifted from the previously inactive operating state into the active state. However, the amplifier C cannot shift into its active operating state because the latter is unstable as long as the actuated coupling capacitor T_b , which then also fulfills for the amplifier C the feedback condition via the alternating-current coupling path $S_r-T_b-c_2$, possesses the aforesaid increased effective capacitance.

It is for this by actuating the capacitor T_b there can and must be automatically obtained only the situation or condition of operating states wherein the amplifier B is the only one in an active operating state. A corresponding actuation of the capacitor T_c in the depicted condition of FIG. 1 will automatically bring about in analogous manner the operating state where the amplifier C is in its active operating state. On the other hand, actuation of the capacitor T_a will not disturb the operating state for the active amplifier A in that the alternating-current signals generated at the amplifier output S_a are not fed back to the inputs of such amplifier A with sufficient amplitude, via the small residual capacitance values of the capacitors T_b and T_c in circuit with the inputs a_1 , a_2 of the amplifier A to shift amplifier A out of its active amplifying operating state, whereas alternating-current disturbance signals amplified at the amplifier A are delivered via the capacitor T_a , which has been adjusted to the higher effective value by actuation thereof, only to the inputs c_1 and b_2 of the inactive amplifiers B and C and thus remain ineffectual. It is here further to be mentioned that basically instead of using the capacitors T_a , T_b , T_c it would be possible to employ other variable coupling means or impedances which can be mechanically actuated, such as inductances, resistances or also switching devices. Similarly it is also basically possible to devise the direct-current coupling of the amplifiers and the arrangement of the coupling means which can be actuated such that in each of n possible operating states of the circuit arrangement one and only one of the n amplifiers is operated in an inactive operating state and all of the other amplifiers are operated in an active amplifying operating state.

The block circuit diagram of FIG. 2 corresponds in its function to that of the arrangement of FIG. 1. Here there have been depicted in detail the storage i.e. amplifier stages and their connections with the coupling capacitors.

Hence, it will be seen that each storage stage A, B and C embodies two auxiliary or signal amplifiers A_1 , A_2 and b_1 , B_2 and C_1 , C_2 respectively, each having a respective special control input a_1 , a_2 and b_1 , b_2 , and c_1 , c_2 respectively. The respective inverting output i of both auxiliary amplifiers of each storage stage A, B, C are additively coupled via a respective summation ele-

ment Σ with a respective collector conductor L_a , L_b and L_c respectively. Such collector conductors L_a , L_b and L_c each lead to the input of a main amplifier A_o , B_o and C_o respectively. Each of these main amplifiers A_o , B_o and C_o possesses an inverting output i_o and a non-inverting output p_o . The inverting outputs i_o of all of the main amplifiers A_o , B_o , C_o are directly connected with one another via the common lead or line S_r and each such inverting output i_o is connected with the associated non-inverting output p_o via a respective associated coupling means illustrated as capacitor T_a , T_b and T_c respectively, as shown. The connection point of the non-inverting outputs p_o of the three main amplifiers A_o , B_o , C_o with the associated coupling capacitors T_a , T_b and T_c respectively, which correspond in their construction and mode of operation to the correspondingly designated components of FIG. 1, are each connected analogous to the circuit arrangement of FIG. 1 with an input of the other storage stages, as shown. Thus, the output p_o of the main amplifier A_o and the capacitor T_a are connected with the input b_2 of the storage stage B and the input c_1 of the storage stage C, and in analogous manner the capacitors T_b and T_c associated with the storage stages B and C respectively, are each connected with the inputs c_2 and a_1 and a_2 and b_1 respectively, of the two other relevant storage stages C and A and A and B respectively.

By means of the shading appearing in FIG. 2 with respect to the amplifiers A_1 , A_2 and A_o of the storage stage A, it is intended to indicate that as in FIG. 1 there is portrayed the operating state wherein the storage stage A has its main amplifier in the active operating state while the storage stages B and C have their respective main amplifiers in the inactive operating state, which situation for instance can be altered by actuating the capacitor T_b into a condition where the stage B is active storage or by actuating the capacitor T_c into the condition where the storage stage C is active, whereas any possible actuation of the capacitor T_a remains ineffectual, that is to say, there is maintained the circuit state where the main amplifier of the storage stage A is in its active operating state.

In FIG. 3 there is depicted as a preferred exemplary embodiment a complete circuit diagram of the embodiment of multistable circuit arrangement depicted in FIG. 2, wherein there has also been shown the necessary connection to the positive and negative terminals of a direct-current voltage source GQ. It will be observed that the control inputs a_1 , a_2 of the storage stage A lead to the respective base electrodes 20 of both of the transistors A_1 and A_2 which are effective as respective auxiliary amplifiers A_1 and A_2 . The collector electrodes 22 of the transistors A_1 and A_2 are coupled with a collector conductor L_a which, in turn, is connected via a resistor R_1 with the positive (+) terminal of the direct-current voltage source GQ and with the base 24 of a transistor A_o which has been connected and is effective as a coupling main amplifier. The emitter electrodes 26 of the transistors A_1 and A_2 are directly connected with the negative (-) terminal of the direct-current voltage source GQ. Operatively associated with each of the transistors A_1 and A_2 is a control transistor H_1 and H_2 respectively, for controlling the base potential. The base electrodes 28 and collector electrodes 30 of such control transistors H_1 and H_2 are likewise coupled with the collector conductor or line L_a , whereas their emitter electrodes 32 are connected with the re-

spective base 20 of the associated auxiliary amplifiers A_1 and A_2 respectively, i.e., at their input lines a_1 and a_2 respectively. The collector electrode 34 of the main amplifier transistor A_0 forms the inverting output i_o of the storage stage A. It is also connected via a resistor R_2 with the positive (+) terminal of the direct-current voltage source GQ . The emitter electrode 36 of the main amplifier transistor A_0 forms the non-inverting output p_o of the storage stage A.

Similar to the showing of FIG. 2 here also the inverting output i_o of the storage stage A is coupled with the corresponding outputs of the storage stages B and C via the conductor or common lead S_r and with the associated coupling capacitor T_a , the other terminal of which is connected with the emitter 36 i.e., the output p_o of the main amplifier transistor A_0 and with the input b_2 of the storage stage B as well as with the input c_1 of the storage stage C. Both of the other storage stages B and C correspond in their construction and their circuit connections completely to the described storage stage A, as will be apparent by referring to FIG. 3. It is advantageous to ensure that all of the auxiliary amplifier transistors A_1 , A_2 , B_1 , B_2 , C_1 , C_2 and the control transistors H_1 , H_2 of all storage stages have identical operating characteristics and are fabricated in a single working operation upon a common base substrate. The effective surfaces of the main amplifier transistors A_0 , B_0 , C_0 should be greater than the corresponding surfaces of the other transistors.

The circuit arrangement depicted in FIG. 3, as concerns its construction and its mode of operation, corresponds to that of FIG. 2. It is assumed that according to the showing of FIG. 3 there is momentarily realized a situation or condition wherein the storage stage A is in its active operating state and the storage stages B, C are in inactive operating states and that the coupling capacitors T_a , T_b , and T_c are non-actuated. Then the actively amplifying transistors A_1 , A_2 receive control currents of minimum magnitude via their inputs a_1 and a_2 respectively, from their therewith connection emitter outputs p_o of the main amplifier transistors B_0 and C_0 respectively. The collector-emitter currents of the transistors A_1 and A_2 then possess relatively low values which are of the same magnitude, and the potential of the collector conductor L_a is relatively high. The main amplifier transistor A_0 of the storage stage A is then likewise driven into its active amplifying operating state and delivers from its emitter output p_o to the inputs b_2 and c_1 relatively high control currents. By means of these input currents the transistors B_2 and C_1 are each driven into their saturation region with maximum collector-emitter currents. Consequently, the collector conductors L_b and L_c possess minimum potential. This again causes the main amplifiers transistors B_0 and C_0 to operate in their blocking region, with minimum emitter currents at the inputs a_1 and a_2 of the amplifier stage A. The inputs b_1 and c_2 of the transistors B_1 and C_2 respectively, receive from the outputs p_o of the main amplifier transistors C_0 and B_0 respectively, just as the inputs a_1 and a_2 , minimum control currents. Under the additional action of the minimum potential of the collector conductors L_b and L_c these transistors B_1 and C_2 , as concerns the alternating currents, are practically inactive. Furthermore, since the associated coupling capacitors B_o and C_o are blocked the storage stages B and C are in a totally inactive operating state. The described state or condition of the circuit arrangement of

FIG. 3 with active storage stage A and inactive storage stages B and C is stable and can only be shifted into its other state by actuating one of the coupling capacitors T_b or T_c . For instance, the capacitance of the coupling capacitors T_b can be brought to a considerably greater effective value by actuating the same. As a result, there becomes effectual an in-phase alternating - current feedback loop or path for the active transistor A_1 of the storage stage A, namely from the input a_1 via the inverting collector output of the transistor A_1 to the collector conductor L_a and via the active main amplifier transistor A_0 to its inverting collector output i_o to the conductor S_r and the coupling capacitor T_b , the capacitance of which has been increased back to the input a_1 of the transistor A_1 . Upon the occurrence or begin of a self oscillation thus brought about in the transistor A_1 this transistor A_1 is shifted or controlled to operate in its saturation range, with the result that the potential of the collector conductor drops to a minimum value and the main amplifier transistor A_0 becomes non-conductive. As a result, its emitter current from the output p_o to the inputs b_2 and c_1 of the transistors B_2 and C_1 drops to the minimum value just as for the transistors B_1 and C_2 . Consequently, each of the storage stages 15 A, B, and C could shift temporarily to an active operating state. However, the active operating state is stable only for the storage stage B during actuation of the coupling capacitor T_b , because then the active amplifying state for the transistors A_1 and C_2 of the storage stages 20 A and C respectively, coupled with the actuated capacitor T_b , is unstable. Hence, under the aforementioned prerequisites the stage B becomes active, with transistors B_1 , B_2 and B_0 active and amplifying. Consequently, increased input currents are transmitted to the transistors A_1 and C_2 coupled with the emitter output p_o of the storage stage B via the transistor inputs a_1 and c_2 , and which input currents control such transistors so as to operate in the saturation region and indirectly the main amplifier transistors A_0 and C_0 to operate in the blocking region, while the transistors A_2 and C_1 become ineffective. The thus positively controlled operating state of the storage stage B with the active transistors B_1 , B_2 and B_0 brought about by the undertaken actuation of the coupling capacitor T_b is thus stable, and this stable state is maintained under the influence of the relatively high input currents from the emitter output p_o of the storage stage B to the inputs a_1 and c_2 of the transistors A_1 and C_2 respectively, even if the capacitor T_b is no longer actuated. Only after the subsequent actuation of 25 one of the other coupling capacitors T_a or T_c is it possible to again bring about an appropriate change in the state or condition of the circuit arrangement.

FIG. 4 depicts in the illustration according to FIG. 1 of the storage stage A a tenfold stable circuit arrangement, instead of only the threefold stable circuit arrangement of FIG. 1. Accordingly, each storage stage A, B, . . . K (see FIG. 5), instead of having a total of three amplifiers each with two inputs, has a total of ten amplifiers A, B, . . . K each with nine inputs, for instance a_1 , a_2 , . . . a_9 , but likewise each has only one main amplifier A_0 , B_0 , . . . K_0 . Each of these main amplifiers possess a respective inverting output i_o , and a respective non-inverting output p_o . Each of the main amplifiers has associated therewith a coupling capacitor T_a , T_b , and so forth.

Hence, with the circuit arrangement of FIG. 5 it is possible to automatically and positively bring about, for

instance by briefly actuating the capacitor T_b the operating state where the storage stage B is in its active operating state and by actuating the capacitor T_k the operating state where the amplifier stage K is in its active operating state, as should be readily understood from what has been discussed above.

The circuit arrangements of FIGS. 3, 4 and 5 can be readily fabricated as monolithic integrated circuits and, for instance, employed an numerical input arrangements for computers or calculating machines.

While there is shown and described present preferred embodiments of the invention, it is to be distinctly understood that the invention is not limited thereto, but may be otherwise variously embodied and practiced within the scope of the following claims. Accordingly,

What is claimed is:

1. A multistable circuit arrangement comprising a multiplicity n of storage stages each operatively associated with a respective coupling means in a one-to-one correspondence, the value of n being equal at least to three, a common lead, each coupling means comprising an impedance element with first and second terminals thereof between which an impedance value is variable by actuation of the coupling means, each storage stage having first and second operating states and comprising a main amplifier provided with input and output terminals between which in the first operating state an amplified signal is transferred through the main amplifier and in the second operating state the signal transfer through the main amplifier is blocked, each main amplifier having one output terminal connected to the common lead, each coupling means having its first terminal connected to the common lead and its second terminal connected to an input terminal of a main amplifier in each storage stage except its own operatively associated storage stage, any given selected storage stage operating in one given operating state and the remaining storage stages operating in the other operating state.

2. A multistable circuit arrangement as defined in claim 1, wherein the impedance element of each coupling means comprises a variable capacitor.

3. A multistable circuit arrangement comprising a multiplicity n of storage stages each operatively associated with a respective coupling means in a one-to-one correspondence, the value of n being equal at least to three, a common lead, each coupling means comprising an impedance element with first and second terminals thereof between which an impedance value is variable by actuation of the coupling means, each storage stage having first and second operating states and comprising (a) a main amplifier provided with an input terminal and output terminals between which in the first operating state an amplified signal is transferred through the main amplifier and in the second operating state the signal transfer through the main amplifier is blocked, the output terminals of said main amplifier comprising a first and a second output terminal, one of which is inverting and the other one is non-inverting with respect to the input terminal, (b) $n-1$ auxiliary amplifiers each having input and output terminals, and (c) an adding circuit having $n-1$ input terminals and an output terminal, each storage stage being connected in circuit such

that the output terminals of the auxiliary amplifiers are each connected to a different input terminal of the adding circuit, the output terminal of which is connected to the input terminal of the main amplifier, said main amplifier having its first output terminal connected to the common lead, each coupling means having its first terminal connected to the common lead and having its second terminal connected to the second output terminal of the main amplifier of its own associated storage stage and also to the input terminal of one auxiliary amplifier in each storage stage except its own associated storage stage, each storage stage thus receiving input from all of the other storage stages at separate auxiliary amplifiers thereof, any given selected storage stage operating in one given operating state and the remaining storage stages operating in the other operating state.

4. A multistable circuit arrangement as defined in claim 3, wherein the impedance element of each coupling means comprises a variable capacitor.

5. A multistable circuit arrangement comprising a constant voltage source having first and second terminals, a multiplicity n of storage stages each operatively connected with a respective coupling means in a one-to-one correspondence, the value of n being equal at least to three, a common lead, each coupling means comprising an impedance element with first and second terminals between which an impedance value is variable by actuation of the coupling means, each storage stage comprising (a) a main transistor, (b) $n-1$ auxiliary transistors, (c) $n-1$ control transistors, each transistor having base, emitter and collector terminals, and (d) first and second resistors each having first and second terminals, each storage stage being connected in circuit such that the collector terminals of the auxiliary transistors and of the control transistors and the base terminals of the control transistors are all electrically connected with the base terminal of the main transistor and with the first terminal of the first resistor, the second terminal of said first resistor being connected to the second terminal of the voltage source and the collector terminal of the main transistor being connected to the common lead and to the first terminal of the second resistor, the second terminal of the second resistor being connected to the second terminal of the voltage source, the emitter terminals of the auxiliary transistors being connected together and to the first terminal of the voltage source, each coupling means having its first terminal connected to the common lead and having its second terminal connected to the emitter terminal of the main transistor of its own associated storage stage and also to the base terminal of one auxiliary transistor in each storage stage except its own associated storage stage, each storage stage thus receiving input from all of the other storage stages at separate auxiliary transistors thereof, any given selected storage stage having its main transistor operating in the amplifying range of its characteristic whereas all other storage stages have their main transistors operating in the non-amplifying blocking range of their characteristic.

6. A multistable circuit arrangement as defined in claim 5, wherein the impedance element of each coupling means comprises a variable capacitor.
